UNITED STATES PATENT OFFICE.

RICHARD SCALES, OF NEWARK-UPON-TRENT, ENGLAND.

MEANS FOR SECURING BUSKS TO CORSETS.

SPECIFICATION forming part of Letters Patent No. 728,305, dated May 19, 1903.

Application filed February 17, 1903. Serial No. 143,818. (No model.)

To all whom it may concern:

Be it known that I, RICHARD SCALES, corset manufacturer, a subject of the King of Great Britain, residing at Waveney House, 5 London Road, Newark-upon-Trent, county of Nottingham, England, have invented a new or Improved Means for Securing Busks to Corsets, (in respect of which I applied for Letters Patent in Great Britain on the 8th of January, 1903, under No. 546,) of which the following is a specification.

My invention relates to a new or improved means for securing busks to corsets, so that in case of breakage the said busks can be at 15 once removed and new busks can be easily and quickly replaced without sewing and without any detriment or disfigurement to the corset.

In the drawings, Figure 1 shows two adjacent edges of a corset with the busks as secured or fixed in place according to my invention, each of the busks being partly exposed. Figs. 2 and 3 are separate detached views of types of the special form of clip employed by me.

In carrying out my invention I first add a long flap A down the extreme front of the corset, which flap is of itself distinct, being cut and stitched at the top and bottom of the corset in such a manner as to allow the said flap A to perform the under-mentioned purpose. I form the usual openings in the flap A for the fasteners a and a' of the busks B and pass them through in the ordinary way. I then 35 fold this flap A around the busk B, so as to embrace and cover the said busk, as in Fig. 1, which method of folding the said flap causes the busks to be self-held in place on the figure. Then to hold the material thus folded and to 40 render the grip effectually secure I make use of specially-designed spring clips or clamps

C and C', employed as shown, for adaptation on the fastenings a and a' of the busk to hold the busk B and flap A strongly embraced, thus securing the busks B in the corsets. 45 These said clips or clamps C and C' are so placed on the busks that the fastenings on the one busk and the studs on the other busk hold them immovable. I make these spring clips or clamps C and C' of any suitable 50 substance—such, for instance, as tempered steel, and so prepared to prevent any discoloration of fabric. These clips or clamps C and C' securely embrace the busks B and edges of the folded fabric A in such a way 55 that in the case of its being necessary to remove the busks the operation of replacing the busks can be performed without any appreciable trouble, cost, or loss of time. Both busks are similarly folded and held by the 60 clips or clamps C and C' aforesaid.

I do not confine my invention to the particular shape, design, or construction of spring clips or clamps shown in the drawings, as same may be modified to suit different requirements.

Having now particularly described and ascertained the nature of my said invention and in what manner the same is to be performed, I declare that what I claim is—

In combination in a corset, a busk, fasteners thereon, a free flap on the corset, a U-shaped clip adapted to embrace the busk to hold the free flap on the same, said clip having arms to fit over the fasteners. 75

In witness whereof I have hereunto set my hand in presence of two witnesses.

RICHARD SCALES.
